Primary Examiner — Sandra S Snapp
Assistant Examiner — Katherine Glennon

CLAIM

The ornamental design for a badge holder with timer, as shown and described.

DESCRIPTION

FIG. 1 is a left perspective view illustrating a badge holder with timer embodying my new design;

FIG. 2 is a top plan view illustrating a badge holder with timer embodying my new design;

FIG. 3 is a bottom plan view illustrating a badge holder with timer embodying my new design;

FIG. 4 is a left side view illustrating a badge holder with timer embodying my new design;

FIG. 5 is a right side view illustrating a badge holder with timer embodying my new design;

FIG. 6 is a right upper perspective view illustrating a badge holder with timer embodying my new design; and,

FIG. 7 is a right lower perspective view illustrating a badge holder with timer embodying my new design.

The broken line disclosure illustrates environment and forms no part of the claimed design.
